CHAIR-BED FOR HOUSEHOLD PETS

Irma Summa Bresch, University City, Mo.

Application July 30, 1956, Serial No. 42,458

Term of patent 14 years

(Cl. D12—2)

FIG. 1.

FIG. 2.

FIG. 3.

FIG. 4.

Fig. 1 is a top plan view of a chair-bed for household pets embodying my new design;

Fig. 2 is a front elevational view thereof;

Fig. 3 is a side elevational view thereof, and

Fig. 4 is a perspective view thereof.

I claim:

The ornamental design for a chair-bed for household pets, substantially as shown.
